UNITED STATES PATENT OFFICE

LEO D. JONES, OF PHILADELPHIA, PENNSYLVANIA, ASSIGNOR TO THE SHARPLES SPECIALTY COMPANY, OF PHILADELPHIA, PENNSYLVANIA, A CORPORATION OF DELAWARE

METHOD OF DEWAXING PETROLEUM OIL

Application filed October 7, 1925. Serial No. 61,125.

My invention relates to a process of refining petroleum, and particularly to the refining of that part of crude petroleum which remains after gas, naphtha and burning oils have been distilled off, such part of the petroleum, formerly called tar, being herein referred to as long residuum of petroleum, and to the refining of certain distillates of such residuum. The term long residuum is intended to mean a still residue which includes a larger percentage of the crude oil than would be contained in cylinder stock residuum made from the same crude, and in general includes most of the lubricating content of the oil.

It is an object of my invention to provide a process whereby viscous lubricating oils of low cold test are efficiently and economically produced from long residuum of petroleum and distillates of such residuum that contain "non-pressable" wax, contain oil of low specific gravity and low boiling point, and have a low flash point, e. g., a flash point lower than 450° F. Oils that "contain non-pressable wax" are oils from which the contained wax cannot be removed to a satisfactory degree in a single operation by precipitating the wax therein by chilling and then pressing the oil through pervious material while the wax is held back by the pervious material, although a fraction may be taken from such oils by distillation from which wax may be removed to a satisfactory degree by chilling and pressing. The wax in such a fraction is light wax (i. e., of lower boiling point than other wax in the oil) and is the wax hereinafter referred to as light wax.

In the removal of non-pressable wax from oil it has formerly been the practice to purify or decolorize the oil, before dewaxing it, by treatment with acid or clay or both with the intended purpose of rendering the removal of wax more complete and for the purpose of decolorizing the oil. This practice, wherein the oil was purified before being dewaxed, worked satisfactorily with oils having a comparatively high flash point, e. g., a flash point above 450° F. With oils having a comparatively low flash point, for example oils having a flash point below 450°

F., difficulty was encountered in securing a desired degree of wax removal as the light wax was not removed with the result that the cold test of the oil was unsatisfactory and in fractionation of the dewaxed oil light wax accumulated in the viscous neutral fraction giving that product a higher cold test than the cold test of the viscous fraction or bright stock residue although it is desirable that the viscous neutral fraction have as low a cold test as possible. If oil that contains non-pressable wax is purified by acid treatment or by clay treatment or by both of such treatments to such an extent that it meets commercial requirements as to color and purity for a red or yellow oil, and if such oil is in a diluted state either as a result of the presence of gas oil in it or as a result of the addition of naphtha, and if the diluted oil is then chilled to precipitate the wax, then some of the wax may float on the solution and therefore pass out with the oil in dewaxing by subsidence as in a centrifugal dewaxing operation, and whatever wax is heavier than the solution is likely to be so hard or firm that it will not flow from a centrifugal separator in such a manner as to permit continuous centrifugal separation thereof from the oil.

I have discovered that if oil containing non-pressable wax, including light wax, is not completely purified or decolorized before it is dewaxed (for example, if such oil contains impurities other than hard asphalt or such impurities as may readily be removed by clay treatment), the dewaxing of the oil may be effected, in accordance with my invention, to a satisfactorily complete degree. The separation of wax precipitated by dilution and chilling of such wax-bearing oil may be carried out centrifugally. References to hard asphalt herein refer to asphalt which is precipitated when the oil is extensively diluted with light naphtha and which if then compressed together forms a brittle cake and which impairs centrifugal dewaxing by producing hard accumulations within the centrifugal bowl. A reference herein to impurities other than hard asphalt or to impurities that may readily be removed by

clay treatment is a reference to impurities or constituents contained in a residuum formed by steam-distilling gas, naphtha and burning oils from wax-bearing crude petroleum and which are (a) not hard asphalt, and are (b) most readily (i. e., most economically) removable by clay treatment. Clay treatment makes the color of oil lighter, but the impurities or constituents which are removed by clay treatment have not as yet, although decolorizing by clay treatment is old in the art, been identified chemically and it is not known what other changes and removals occur in such decolorizing. It has been common practice to so purify the long residuum or a distillate thereof prior to dewaxing and the above described difficulties obtain in the dewaxing. But, in accordance with this invention a residuum or a distillate thereof that is made from wax-bearing crude petroleum by steam distillation and merely substantially freed of hard asphalt, is diluted and chilled and the wax is precipitated in a form in which it may be separated from the oil by subsidence, and particularly by centrifugal separation. In other words I have discovered that if oil containing light wax also contains a sufficient quantity of such impurities as are above mentioned, the light wax passes from the oil, particularly in a centrifugal dewaxing operation, in the same manner that heavy wax present passes from the oil and in the same manner that the wax passes from decolorized steam refined cylinder stock. In other words I have discovered that if oil contains light wax and also contains a sufficient quantity of such impurities as are above mentioned, chilling of the oil to a sufficiently low degree will effect such precipitation that the wax may be removed to a satisfactorily complete degree by a suitable wax removing operation. I have also discovered that a portion of the impurities that are present pass from the oil with the waxes, that the ratio of impurities so removed with the wax to the total impurities present before wax removal is at least as great as the ratio of removed wax to the original mixture of oil and wax, and that the impurities that so pass out with the waxes are those impurities that are difficult to remove from the oil in subsequent purification as with clay, in that it is these impurities which use up the purifying property of a large portion of the clay that is used.

The long residuum of some petroleums naturally contains those impurities which when present will insure a satisfactory degree of removal of non-pressable wax when the long residuum is dewaxed.

The long residuum of other petroleums will be found to contain a small amount of asphalt. In other words the long residuum of some petroleums will contain impurities other

than those that may readily be removed by clay treatment and which will interfere with the operation of my process. Such excessive impurities include what is commonly termed "hard asphalt". I have discovered that if long residuum containing such impurities is given a mild acid treatment that will leave in the long residuum such impurities as may be removed readily by clay treatment, dewaxing of the resulting product is satisfactorily accomplished. Objectionable asphalt is asphalt that precipitates out during the dilution and chilling of the oil that effects the precipitation of non-pressable wax. Such hard asphalt interferes with the effective precipitation of the wax. Moreover, if it be desired to remove by centrifugal devices from oil containing hard asphalt such wax as precipitates in spite of the presence of hard asphalt, it is found that the hard asphalt impedes the discharge from the centrifugal bowl of the wax separated therein. The identification of the particular impurities of oil that are referred to herein may be further facilitated by a consideration of a long residuum of wax-bearing oil which is produced by steam distillation and which contains enough hard asphalt to produce an appreciable precipitate upon extensible dilution of the residuum with light naphtha. While such asphalt might be removed by clay treatment of the residuum it is more economical, and it is usual, to remove such asphalt by mild acid treatment, but the impurities remaining after such mild acid treatment are removed economically, and for that reason readily, by clay treatment. The mild acid treatment effectively reduces the hard asphalt content of the residuum and although the operation is old the impurities removed in such treatment have not been chemically identified and its not known what changes and removals occur other than reduction of the hard asphalt content. Therefore, impurities other than those that may readily (i. e., economically) be removed by clay treatment are those impurities which are removed by the preliminary mild acid treatment and they include hard asphalt.

The long residuum of still other petroleums will be found to contain more asphalt than can be economically removed by acid treatment for the purpose of bringing the oil to a condition wherein dewaxing in accordance with my process is satisfactorily carried out. I have discovered that such long residuum may be brought to a condition wherein it may be dewaxed satisfactorily in accordance with my process, by distillation that is so carried out that substantially all of the lubricating content of the long residuum is distilled over without cracking and a sufficient quantity of impurities of the character above mentioned is distilled over into the distillate. Such distillation may be steam distillation

at atmospheric pressure or vacuum distillation or a combination of both. The distillate so produced is then treated in accordance with my invention. Distillates from pipe stills have also been satisfactorily treated in accordance with my invention.

While some oil distillates may, as above set forth, be made to contain impurities in the presence of which non-pressable wax may be removed in the dewaxing operation, in accordance with my invention, other distillates containing non-pressable wax may contain, as in the case of the long residuum above referred to, excessive impurities such as a small amount of asphalt. I have found that if such distillates are given a mild acid treatment that will leave in them such impurities as may be removed readily by clay treatment, dewaxing of the resulting product is satisfactorily accomplished in accordance with my invention.

If the stock that is to be treated in accordance with my invention, regardless of whether it is a distillate or a long residuum of petroleum, does not contain a sufficient quantity of impurities to insure, as above set forth, that non-pressable wax will be removed from the oil to a sufficiently complete degree, impurities may be brought into the stock that is to be dewaxed by blending such distillate or long residuum that is lacking in impurities with other products containing an excess of such impurities other than hard asphalt.

Regardless of whether the product that is to be dewaxed contains the necessary impurities naturally or by blending, and regardless of whether the product that is to be dewaxed has been brought to the proper condition by acid treatment or by non-cracking distillation as above described, the product that is to be dewaxed possesses in any case substantially the same characteristics. A product that is to be dewaxed and which contains enough of such impurities that dewaxing may be satisfactorily effected in accordance with my invention will be herein referred to as dewaxing stock regardless of whether it was obtained naturally, by blending, by acid treatment or other purification or by distillation.

In carrying out my process crude oil is distilled without cracking to remove the gas, naphtha and burning oil. If the long residuum thus obtained or a desired distillate thereof contains the impurities designated as desirable above, such stock then constitutes a dewaxing stock. If the long residuum thus obtained or a desired distillate thereof does not contain the impurities designated above as desirable, such stock is brought by the appropriate application of the steps of my invention above set forth, to a condition wherein it constitutes a dewaxing stock.

A feature of this invention is that by the steps leading to its formation or by blending,

a long residuum or a distillate is obtained or formed that contains impurities that naturally occur in such distillates or residues and that are most readily or economically removable by clay treatment, and the presence of such impurities causes the wax as a whole that is precipitated by chilling to be of such specific gravity and such character or degree of plasticity that it may be removed by subsidence, and particularly by centrifugal dewaxing. While the impurities other than hard asphalt may affect the specific gravity of the precipitated wax they nevertheless tend to cause precipitated wax to be amorphous in form and they may therefore be said to constitute an "amorphizing" agent.

If the long residuum (such as long residuum of Cabin Creek crude oil) or a distillate thereof does not contain a sufficient concentration of impurities other than hard asphalt, to render the precipitated wax readily removable in a single operation, when that residuum or distillate is produced in the most desirable way, or if more extended distillation for the purpose of carrying such impurities into the dewaxing stock is impractical or would produce an oil of undesirable viscosity, impurities may be added by blending with the dewaxing stock oil products containing such impurities in excess, as above suggested, and either containing or free of wax. However, in some cases such blending would be excessive and impair the efficiency of the dewaxing plant, as in the case of a distillate taken for the purpose of producing a non-viscous lubricating oil, and in such cases the process of my copending application Ser. No. 147,383, filed November 9, 1926, may be advantageously employed, that process involving the addition of distinctly amorphous wax, or of petroleum products containing such wax, either free of or containing "amorphizing" impurities.

In carrying out my invention the dewaxing stock, after its temperature is reduced to about 120° F. if previous treatment has raised its temperature above that point, is diluted with about 55% to 65%, e. g., 62%, of straight cut naphtha having a specific gravity of approximately 62° Bé. and the mixture is heated to about 100° F. to effect complete solution of the contained wax. This mixture is then gradually cooled and chilled to about -10° F. at which point the wax present should be precipitated out of solution to a satisfactory extent. The wax is then separated from the oil, preferably by centrifugal treatment in which the chilled diluted mixture is introduced into the revolving rotor of a centrifugal machine operated, for example, in accordance with the patent to P. T. Sharples, No. 1,232,104, the oil and wax being continuously and separately discharged. The naphtha is removed from the dewaxed oil and the remaining product is

then treated in a manner varying with the character of final products desired. After the naphtha is removed therefrom the oil is a dewaxed product of dark color. This 5 dewaxed product may be treated in several ways, the subsequent treatment varying according to the particular final products desired. The dewaxed product may be fractionated, as by steam distillation, to produce 10 non-viscous oil distillate, viscous neutral oil distillate, and, provided the dewaxing stock contains sufficiently viscous material, cylinder stock residue. Both the non-viscous oil and the viscous neutral oil will be of light 15 color and will have a cold test below 25° F. and may be regarded as finished lubricating products. The cylinder stock will contain all of the impurities present in the dewaxing stock except those removed in the dewaxing operation and will be of dark color. 20 If desired, this cylinder stock may be made into a bright stock by clay treatment and will then have a cold test of 20° F. or lower.

As one alternative the de-waxed oil, e. g., 25 the oil discharged from the centrifuge may be treated with or filtered through clay before fractionation. This clay treatment or filtration may be carried out either before or after the naphtha is removed. In this case 30 the product may then be fractionated, as by steam distillation. The products of this procedure will include non-viscous oil, viscous neutral oil and, provided the dewaxing stock contains sufficiently viscous material, bright 35 stock residue. The non-viscous oil, viscous neutral oil and any bright stock residue will have the same properties as the similar products produced in accordance with the above described procedure wherein the clay treatment 40 was limited to the cylinder stock in which all of the impurities were concentrated by distillation.

As another alternative the oil discharged 45 from the centrifugal separator may be treated with or filtered through clay and freed of the diluting naphtha by steam distillation, by whichever order of procedure is most convenient, and the resulting light colored low cold test product may be used as 50 a finished lubricant or as blending stock.

An important advantage of my invention resides in the fact that I am thereby enabled to more completely remove non-pressable wax, including light wax that is in itself 55 pressable, from oils of low flash test with the result that I am enabled to dewax, particularly by a centrifugal process, all of the lubricating content of crude petroleum and to obtain not only lubricating oils of low 60 cold test but to obtain a greater proportionate yield of such oil. Previous processes for the dewaxing of oils containing non-pressable wax have been of two kinds. In one such process the wax was removed by filter press- 65 ing and in that case preliminary cracking

treatment was necessary but that converted a large proportion of the lubricating content of the oil into non-lubricating products. In the other of such processes the amorphous wax was removed without change of state by 70 centrifugal dewaxing of previously purified or decolorized stock. I obtain substantially three times as much viscous neutral oil as is obtained by such processes wherein cracking distillation is restored to for the purpose of 75 bringing the wax into a form in which it is removable by a filter pressing. Such previous centrifugal processes have not attained the improvement in cold test that results from centrifugally dewaxing the oil, in accordance 80 with my invention, without previously decolorizing the oil. Thus the final product attained by the practice of my invention will have a cold test of 25° F. or lower even though the dewaxing stock was of low 85 flash test whereas previous centrifugal processes when applied to dewaxing stock of low flash test produced a final product having a cold test of 50° F. or higher.

Another important advantage of my invention resides in the fact that when wax is removed from dewaxing stock before decolorization of the dewaxing stock, impurities that are of such character that they are the most difficult to remove from the oil will 90 pass from the oil when the oil is diluted and chilled and the wax separated, as by centrifugal separation.

Another important advantage of my invention resides in the fact that substantial economies are effected in the reduction of the cost of decolorization. Wax separated in accordance with my invention forms a substantial fraction, 15% to 30% in most cases, of the original dewaxing stock, and as above stated 100 the ratio of impurities removed with the wax to the total impurities of the dewaxing stock is at least as great as the ratio of wax to the mixture of wax and oil. But the wax may, without application of decolorizing 105 treatment thereto, be converted and the total cost of decolorization is accordingly reduced. The separated wax although it contains the impurities left in it in the practice of my invention, may be subjected to a cracking distillation and the distillate then filter-pressed and sweated in order to produce paraffine, the color being concentrated in the still bottoms. Or such separated wax may be used 110 as a pressure still stock for the production of naphtha. If the dewaxed product is separately, i. e., after dewaxing, decolorized by treatment with clay an advantage is gained 115 in the fact that it is easier to pass the dewaxed product through the clay than it is to pass a wax-containing product through the clay.

Another important advantage of my invention resides in the fact that my process is extremely flexible with respect to the final 120

products produced, for example with the same dewaxing procedure it is possible to produce the following low cold test products: dark long residuum, bright long residuum, dark colored cylinder stock of any fire test, bright stock and pale non-viscous oil and pale viscous neutral oil. In fractionating the dewaxed product the distillation may be carried to any point desired so that cylinder stocks may be produced having any required fire test and in the same way a great variety of straight run viscous neutral oils can be produced that have a wide range of flash tests and that have viscosities up to as high as one thousand seconds Saybolt at 100° F.

Another important advantage of my invention resides in the fact that in dealing with wax-bearing crudes containing a very large proportion of asphalt a distillate may be produced by distillation which may be satisfactorily dewaxed by my process and from which may be obtained cylinder stock or bright stock which cannot be obtained from these crudes by any other process and from which a much higher yield of viscous neutral can be obtained than by the customary process involving cracking distillation of the crude and filter pressing to remove the wax.

From the foregoing it is apparent that in the practice of my invention lubricating oils of low cold test and comprising an exceptionally large proportion of viscous neutral oil and which are freed in the dewaxing operation of impurities that are the most difficult to remove may be obtained from dewaxing stock consisting of long residuum or a distillate that naturally contains certain impurities or that is prepared from long residuum or distillate by blending with products that contain desired impurities or that are prepared by simple operations from long residuum or distillate containing asphalt.

In the practice of this invention one feature is that the oil is brought to a condition which causes all of the wax precipitated therein by reduction of temperature to be in that amorphous state in which it can be removed from the oil by processes suitable to the removal therefrom of precipitated amorphous wax, in spite of the fact that the wax in the oil is of such character that if the oil were in some other condition some of the wax present would precipitate in crystalline form. That condition is arrived at in accordance with the present invention by having present in the oil, as a result of the distillation or blending or mixing by which it is produced, a sufficient quantity of impurities above identified and broadly designated herein as "amorphizing" impurities. If those impurities were not present in sufficient quantity all of the wax would not precipitate in that amorphous state. If they are present in sufficient quantity none of the wax will precipitate in crys-

talline form. In the claims a statement that the precipitated wax is in that amorphous state in which it is removable by processes suitable to removal of precipitated amorphous wax means that all of the precipitated wax is so homogeneous and plastic that it is removable by such processes and remains in that condition until it is removed. Also, a reference herein to oil that contains crystalline wax is intended as a reference either to oil which contains an insufficient quantity of "amorphizing" impurities to cause all of the precipitated wax to be in such amorphous state or is free of such impurities and which will upon reduction of temperature produce a wax precipitate of which some part is crystalline; or to oil which may or may not contain a quantity of such impurities sufficient to cause all of the wax precipitated therein by reduction of temperature to be in such amorphous state but which if first freed of such impurities in whole or in substantial part, as by such treatment as would bring the oil to commercially desired color, will upon reduction of temperature produce a wax precipitate of which some part is crystalline; or to oil which may or may not contain a quantity of such impurities sufficient to cause all of the wax precipitated therein by reduction of temperature to be in such amorphous state but which by non-cracking distillation will produce an initial distillate that will upon reduction of temperature produce a wax precipitate of which some part is crystalline. In short, oil that contains crystalline wax is oil from which wax can be recovered that is in non-plastic crystals (even though the oil initially contains impurities that would cause all of the wax precipitated therein by reduction of temperature to be in such amorphous state) by refining methods in which none of the constituents of the initial oil is chemically altered.

While I have described my invention in considerable detail I do not intend that my invention shall be limited to such details but intend that it shall include such variations and modifications as fall within the hereunto appended claims. In this connection, if the long residuum contains so much asphalt that it is desirable for economical reasons to produce the dewaxing stock by distillation of the long residuum and some hard asphalt or still residue is carried over into the distillate, it may be desirable to subject the distillate to a slight acid treatment to eliminate such hard asphalt or still residue prior to dewaxing. While I prefer, in the practice of my invention to separate centrifugally the precipitated wax and the impurities that pass out with it I do not limit my invention to that method of separation in every case; and in this connection I consider that any known method of separating precipitated wax from the oil stock falls within the spirit of my invention

so long as non-pressable wax and impurities other than hard asphalt or such impurities as may readily be removed by clay treatment are present and the advantages derived from the presence of such impurities are attained. 5 For example, I consider separation of wax by the addition of various substances, e. g., wood pulp or paper stock, is within the spirit of my invention. Centrifugal separation, if employed, may include any or all features and expedients ordinarily employed in centrifugal dewaxing operations, such for example as the use of an auxiliary or carrier liquid within the centrifugal bowl. The chilling step of 10 the dewaxing operation may also be modified in known respects.

The claims of this application are directed broadly to the ensuring of the presence in crystalline-wax-containing oil, prior to the 20 dewaxing of such oil and by addition thereto or otherwise and for the purpose of assisting in dewaxing such crystalline-wax-containing oil, of "amorphizing" impurities of petroleum, and specifically to the ensuring of 25 the presence in such oil in such manner and for such purpose of impurities other than hard asphalt and which naturally occur in petroleum oil and are commonly removed therefrom by extensive acid treatment or by 30 extensive clay treatment; and to the dewaxing of oil containing such impurities. My copending application Serial No. 147,883, filed November 8th, 1926 is directed broadly to the regulating of the condition of crystalline-wax-containing oil to the end that wax 35 precipitated therein may be separated therefrom by methods suitable to the removal of precipitated amorphous wax, and broadly to the addition to crystalline-wax-containing 40 oil, for that purpose, of "amorphizing" substances, and specifically to the use of such "amorphizing" substances as amorphous wax alone or amorphous wax together with "amorphizing" impurities of which the use is claimed 45 herein, and which are impurities other than hard asphalt which naturally occur in petroleum oil. A reference in the claims hereof to "amorphizing" impurities is intended as a reference to those impurities other than hard 50 asphalt which naturally occur in petroleum oil and possess the property of causing crystalline wax to precipitate in amorphous form, and is not intended to include wax that occurs in petroleum.

55 Having thus described my invention, what I claim as new and desire to secure by Letters Patent is:

1. The method of dewaxing the residuum remaining after the distillation of gas, 60 naphtha and burning oils from wax-bearing petroleum, which comprises subjecting the residuum to such acid treatment as will substantially remove hard asphalt therefrom while leaving therein other impurities and 65 thereby producing dewaxing stock, and then

dewaxing the dewaxing stock while it contains said other impurities by methods suitable to the removal of precipitated amorphous wax.

2. The method of dewaxing the residuum 70 remaining after the distillation of gas, naphtha and burning oil from wax bearing petroleum, which comprises substantially removing hard asphalt from the residuum while leaving other impurities and non-pressable wax therein and thereby producing dewaxing stock, and then dewaxing the dewaxing stock containing said other impurities by methods suitable to the removal of precipitated amorphous wax. 75

3. In the treatment of petroleum, the method of dewaxing petroleum products containing crystalline wax and amorphous wax which comprises forming a mixture of the oil containing crystalline wax and amorphous wax with "amorphizing" impurities causing wax precipitated from the mixture by chilling to possess sufficient plasticity and high enough specific gravity to be separable from the oil by centrifugal separation, precipitating the wax by chilling and centrifugally separating the oil and wax. 80

4. In the refining of petroleum, the method of removing wax from petroleum oils containing crystalline wax and amorphous wax 95 which comprises forming a mixture of such oil and substances commonly removed from petroleum oil by extensive acid treatment or clay treatment, precipitating the wax by chilling of such mixture and centrifugally separating the wax and oil. 100

5. In the refining of petroleum, the method of removing wax from petroleum oils containing crystalline wax and amorphous wax which comprises so regulating the condition 105 of the mixture of oil and wax with respect to the amount and character of "amorphizing" impurities that the wax, upon precipitation by chilling after dilution, is in a state in which it is capable of being removed from the oil by centrifugal separation, precipitating the wax by chilling, and centrifugally separating the wax and oil. 110

6. In the dewaxing of petroleum oil that contains crystalline wax and amorphous wax 115 the step comprising reducing the temperature of the oil and removing the wax which precipitates in amorphous form, while the oil contains those impurities which naturally occur in petroleum oil and which cause all of the wax precipitated in the oil by reduction of temperature to be in an amorphous state.

7. In the dewaxing of petroleum oil that contains amorphous wax and also crystalline wax that would otherwise precipitate in crystalline form, the steps comprising reducing the temperature of the oil and thereby precipitating wax while the oil contains those impurities which naturally occur in petroleum and cause all of the precipitated wax to 130

be in that plastic state in which it is removable by processes suitable to the removal of precipitated amorphous wax.

8. In the dewaxing of petroleum oil that contains amorphous wax and also crystalline wax the steps comprising reducing the temperature of the oil while it contains "amorphizing" impurities that naturally occur in petroleum oils which cause all of the precipitated wax to be in amorphous form, and centrifugally separating the precipitated wax.

9. In the dewaxing of petroleum oil that contains amorphous wax and also crystalline wax, the steps comprising subjecting the oil to common purification continued to a point at which substantially the only impurities that remain in the oil and affect precipitation of wax upon reduction of temperature thereof are those impurities which cause wax precipitated by reduction of temperature to be in amorphous form, reducing the temperature of the oil while it contains sufficient of such impurities to cause all of the precipitated wax to be in amorphous form, and removing the precipitated wax by methods suitable to the removal of precipitated amorphous wax.

10. In the dewaxing of petroleum oil containing crystalline wax, amorphous wax and impurities that occur in petroleum and impair the precipitation of wax therein upon reduction of temperature thereof, the steps comprising removing such impurities by common purification methods, then reducing the temperature of the oil while it contains sufficient "amorphizing" impurities that occur in petroleum oil to cause all of the wax precipitated by such reduction of temperature to be in amorphous form, and removing the precipitated wax by methods suitable to the removal of precipitated amorphous wax.

11. In the dewaxing of petroleum oil that contains amorphous wax and crystalline wax, the steps comprising producing a mixture of such oil and impurities that naturally occur in petroleum oil and which cause wax precipitated from such oil to be all in an amorphous state, reducing the temperature of the resultant mixture while it contains sufficient of such impurities to cause all wax precipitated as a result of the reduction in temperature to be in an amorphous state, and removing the precipitated wax by methods suitable to the removal of precipitated amorphous wax.

12. In the dewaxing of petroleum oil that contains amorphous wax and crystalline wax, the steps comprising adding to such oil, in such quantity as to cause all wax precipitated therein by reduction of temperature thereof to be amorphous in form, impurities that naturally occur in petroleum oil and which have the property of causing wax precipitated in such oil to be amorphous in form, reducing the temperature of the resulting

mixture and thereby precipitating wax therein in amorphous form, and removing the wax by methods suitable to the removal of precipitated amorphous wax.

13. In the treatment of long residuum of petroleum remaining after distilling off gas, naphtha and burning oils from wax-containing crude petroleum and containing amorphous wax, crystalline wax, hard asphalt and other impurities naturally occurring in petroleum, the steps comprising subjecting such long residuum to non-cracking distillation and thereby producing a distillate having a lower content of hard asphalt than the long residuum and containing sufficient of such other impurities to cause all wax precipitated in the distillate upon reduction of temperature thereof to be in amorphous form, and reducing the temperature of the distillate and thereby precipitating wax therein.

14. In the dewaxing of petroleum oil that contains amorphous wax and crystalline wax and impurities which naturally occur in petroleum and are other than those impurities which occur in petroleum and cause wax precipitated in the oil by reduction of temperature to be in an amorphous state, the steps comprising subjecting such oil to such acid treatment as will substantially remove said impurities contained therein, and then reducing the temperature of the resulting oil while it contains, in such quantities as to cause all wax precipitated therein by reduction of temperature thereof to be in amorphous form, impurities that naturally occur in petroleum oil and cause all of the wax precipitated therein by reduction of temperature to be in an amorphous state.

15. In the dewaxing of petroleum oil containing crystalline wax, amorphous wax, hard asphalt, and "amorphizing" impurities naturally occurring in petroleum, the steps comprising subjecting such oil to non-cracking distillation and thereby producing a distillate having a lower content of hard asphalt than the original oil and containing sufficient of said "amorphizing" impurities to cause all of the wax precipitated in the distillate upon reduction of temperature thereof to be in amorphous form, subjecting the distillate to mild acid treatment to remove asphaltic impurities that interfere with precipitation of wax in the distillate, and reducing the temperature of the acid-treated distillate and thereby precipitating wax therein.

16. In the dewaxing of petroleum oil containing wax the steps comprising reducing the temperature, and thereby precipitating wax therein, of petroleum oil which contains wax and is substantially free of hard asphalt and contains, in a concentration sufficient to cause the oil to be of undesirably dark color and insufficient to impair substantially the precipitation of wax therein by reduction of temperature and in such concentration that

wax precipitated therein by the reduction of temperature is all removable from the oil by continuous centrifugal separation, impurities that naturally occur in petroleum oil and are removable therefrom by clay or strong acid treatment or both of such treatments, and removing the precipitated wax from the oil, together with such of said impurities as accompany the wax removed from the oil, while the oil is at reduced temperature by methods suitable to the removal of precipitated amorphous wax, and thereafter subjecting the residual dewaxed oil to treatment suitable to the removal therefrom of said impurities which remain therein to produce dewaxed oil of desired lighter color.

In testimony whereof, I have signed my name to this specification.

LEO D. JONES.
